R. MURRAY

CAR DOOR LOCK

Filed May 27, 1921

UNITED STATES PATENT OFFICE.

ROY MURRAY, OF JENSEN, UTAH.

CAR-DOOR LOCK.

Application filed May 27, 1921. Serial No. 472,969.

To all whom it may concern:

Be it known that I, ROY MURRAY, a citizen of the United States, residing at Jensen, in the county of Uinta, State of Utah, have 5 invented certain new and useful Improvements in Car-Door Locks; and I do hereby declare the following to be a full, clear, and exact description of the invention, such as will enable others skilled in the art to which it appertains to make and use the same.

This invention relates to new and useful improvements in locks and particularly to locks for freight car doors.

One object of the invention is to provide a device by means of which a car door can be locked automatically from within, and which can be readily and easily opened from without, by one authorized to do so.

Another object is to provide a lock of this 20 character which is simple in construction, formed of few parts, and which can be manufactured at a low cost.

Other objects and advantages will be apparent from the following description when 25 taken in connection with the accompanying drawing.

In the drawing:

Figure 1 is an elevation of a portion of a car wall and door, showing the lock applied 30 thereto and in properly engaged position.

Figure 2 is a horizontal sectional view through the wall and door, immediately above the lock, on the line 2—2 of Figure 1.

Figure 3 is an enlarged vertical sectional 35 view through the outer portion of the lock, on the line 3—3 of Figure 1.

Figure 4 is a horizontal longitudinal central sectional view through the lock, on the line 4—4 of Figure 1.

40 Referring particularly to the accompanying drawing, 10 represents the wall of a car, 11 the doorway, and 12 the sliding door, in connection with which the invention is used.

Secured to one of the vertical edges of 45 the car wall, within the car, and extending toward the doorway, is a metal casting 13, the outer end of which is formed with an upper shorter projection 14, and a lower longer projection 15. This longer projection 50 15 is vertically and longitudinally bifurcated to permit play therein of the triangular latch plate 16, which is pivotally connected, at its smaller end, to the outer end of the longer projection, as shown at 17. In the 55 opposite side portions of the bifurcation are formed with outwardly bowed portions 18

to receive therein the coil springs 19, the lower ends of said springs being retained by the cross members 20, while the upper ends are connected with the member 16. 60 At the inner end of the longer projection 15 is formed a vertical shoulder 21, and formed in this shoulder is a vertical slot or groove 22 in which the adjacent wider end of the plate 16 is guided. The upper edge of the plate 16 has the lateral flanges 23 on which the angle plate 24 is adapted to ride, to rock the plate 16 downwardly, against the tension of the springs 19. This plate 24 is carried by the inner face of the door 12, 70 at the proper distance from the vertical edge to permit the said edge portion of the door to overlap the wall of the car, at the side of the doorway. The projecting portion of the plate 24 is the proper width to 75 pass into the space between the projections 14 and 15, and has the lateral portion 24' to engage behind the portion of the casting 13, which prevents outward swinging movement of the door, when in closed and locked 80 position.

From the above, it will be seen that when the door is moved into closed position, the plate 24 will engage with the triangular plate 16, and depress same so that the plate 85 will pass between the projections 14 and 15. The plate 16 then moves up and snaps behind the plate 24, thus holding the door in closed position. It will be noted that the lock is mounted within the car, so that means 90 must be provided for opening the door, or rather for releasing the lock, from outside of the car.

Carried by the member 13 are the grooved wheels 25, and adjacent an opening 26, in 95 the wall of the car, there is mounted a similar grooved wheel 27. Secured to the inner end of the triangular plate 16, and passing around these wheels 25 and 27, is a chain 28, the other end of which extends through the opening 26 and is provided with a ring 29 which is adapted to be grasped and pulled to swing the plate 16 downwardly out of engagement with the plate 24, thus releasing the lock, and permitting the door to be 100 slid into open position.

Secured to the car wall, over the opening 26, is a plate 30 having an opening 31 the wall of which is outwardly beveled, and against this beveled wall is arranged to engage the ring 29. It will be noted that the chain 28 is of such length that when the 110

plate 16 is in its uppermost position, under the influence of the springs 19, the ring will be firmly held in the opening of the cover plate 30. Carried by the plate 30, and extending outwardly therefrom, is a staple 31, through which, and through the ring, is arranged to be secured the ribbon or wire of the seal 32. By this arrangement the ring cannot be moved a distance sufficient to permit the chain to be drawn out and the plate 16 rocked out of engagement with the plate 24. Thus the lock securely maintains the door in closed position against unauthorized manipulation.

15. What is claimed is:

1. A sliding door lock comprising a door casing carried member having an upper shorter projection and a lower longer projection, the lower projection being vertically and longitudinally bifurcated, the inner end of the longer projection being formed with a vertically grooved shoulder, a triangular plate pivotally mounted in the outer end of the bifurcation and having its wider end disposed in the said grooved shoulder and being normally spring pressed upwardly against the upper projection,

means for manually swinging the triangular plate downwardly, and an angle plate adapted to be mounted on a sliding door for depressing engagement with the triangular plate and seating within the space between the said projections, said angle plate having an offset free end arranged to engage behind the door casing carried member to maintain the door against outward swinging movement.

2. A lock comprising a stationary part including a bifurcated member having a long arm and a short arm, a longitudinally extending and spring pressed member pivotally mounted in the long arm and engaging the short arm with its free end, and a movable part arranged to enter the bifurcation and provided with an off-set portion for engagement with the stationary part to prevent relative lateral movement of the parts.

In testimony whereof, I affix my signature, in the presence of two witnesses.

ROY MURRAY.

Witnesses:

JOSEPH HASLEEN,
ELMER SNOW.
